UNITED STATES PATENT OFFICE.

CARL HUNTEMÜLLER, OF WEISSENBORN, NEAR FREIBERG, GERMANY.

TANK-CHARGING APPLIANCE.

Application filed November 14, 1927, Serial No. 233,294, and in Germany May 11, 1927.

My invention relates to tank-charging appliances, particularly for boilers in which cellulose is treated, and it is an object of my invention to provide an appliance of this kind which combines compactness, simplicity as to construction and operation, low power consumption, and cheapness.

To this end, I equip my appliance with an air screw projecting into the tank, for instance, into the charging pipe of a boiler, and provide suitable means, as an electric motor, for rotating the air screw.

It has already been proposed to provide charging appliances which are placed on the tank or boiler and are removed after the charging has been completed but such appliances as heretofore constructed are large, heavy, and cumbersome in proportion, their power consumption is high and their maintenance cost is excessive on account of the many parts it comprises, some of which are very delicate.

These drawbacks are overcome in my invention and an appliance is provided which, as compared with existing appliances in which the large size and weight are prohibitive under some conditions, can be adapted anywhere on account of the good features recited above.

In a preferred embodiment of my invention, I provide a frame, a vertical shaft in the frame, an air screw on the shaft, and an electric motor on the shaft.

In the accompanying drawing, I have illustrated my appliance in position in the charging pipe of a cellulose boiler but it is understood that this is only by way of example and that I am not limited to this particular case, nor to any one of the constructional details shown and described.

Referring now to the drawing, 3 is a boiler, 4 is its charging pipe, 12 is a funnel projecting downwards from a tank containing a supply of wood chips, 14 is a slide for controlling the opening of the funnel, and 13 is a hand wheel for operating the slide.

1 is a frame adapted to be placed into the charging pipe 4, 2 is a flange on the frame by which it is supported on the top of the pipe 4, 6 is a shaft mounted to rotate in bearings 7, 7 which are connected with the frame 1 by brackets or spiders 8, 8, 5 is an air screw having preferably three blades, and 9 is an electric motor mounted on a bracket 10 above the frame 1. 11 is a charging hopper which may be divided and

detachably secured on the frame 1 and is preferably so arranged as to enclose the motor 9, as shown.

In operation, the appliance is inserted in the pipe 4, as shown, this being readily effected by two men in a few minutes, on account of the small size and light weight of the appliance. The motor 9 is started, and the slide 14 is opened. The chips from the funnel 12 drop onto the air screw 5 and are dispersed by its rapid rotation. The chips are projected into the boiler at corresponding velocity and with considerable force, and it has been found that they will all lie flat and, as it were, seek for a position in which they are sheltered from the intense air circulation. These positions, in which each particle of wood is able to withstand the air currents, are rapidly assumed by the several chips.

Preferably, as illustrated, the frame 1 projects into the boiler 3 to such a distance that the air screw 5 is directly below the base of the pipe 4, as in this position it is particularly effective while, on the other hand, the end of the appliance projects into the boiler only to such depth as not to require recharging of the pipe 4 which is inevitable in appliances projecting far into the boiler. This is another important feature in favour of my appliance as it saves time. The period for charging is very short as the placing in position and removing of the appliance is performed rapidly, and an additional saving is effected by the elimination of recharging.

It will be understood that my appliance as compared with existing appliances, is extremely simple as to its construction and operation, is without delicate parts requiring frequent repair, and its wear is quite small. The simplicity and compactness of the unit are largely due to the arrangement of the motor 9 within the hopper 11 and to the direct connection of the motor with the air screw shaft 6.

My appliance may be further improved, particularly with a view to facilitating its operation, by making the hopper 11 detachable and by dividing it. In this case, the frame with the screw 5 and the motor 9 is placed in position and the hopper 11 is then secured on the frame 1. After charging, the operations of building-up are performed in reversed order. The handling of the appliance is facilitated and this brings about a

further reduction of the charging period, all resulting in a reduction of the initial cost of the product made in the boiler.

I claim:

- 5 1. In a tank-charging appliance comprising a frame, means for supporting said frame in the charging opening of the tank, an air screw in said frame projecting into the tank, and means for rotating said screw.
- 10 2. A tank-charging appliance comprising a frame adapted to be placed in the tank, a vertical shaft in said frame, an air screw on said shaft projecting into the tank, and means for rotating said screw.
- 15 3. A tank-charging appliance comprising a frame adapted to be placed in a tank, a charging hopper on said frame, a vertical shaft in said frame, an air screw on said shaft projecting into the tank, and an electromotor on said shaft and in said hopper.
- 20 4. A tank-charging appliance comprising a frame adapted to be placed in a tank, a detachable charging hopper on said frame, a vertical shaft in said frame, an air screw on said shaft projecting into the tank, and an electromotor on said shaft and in said hopper.
- 25 5. A tank-charging appliance comprising

a frame adapted to be placed in a tank, a detachable charging hopper adapted to be divided and seated on said frame, a vertical shaft in said frame, an air screw on said shaft projecting into the tank, and an electromotor on said shaft and in said hopper.

6. A tank comprising a charging pipe, a frame adapted to be inserted in said pipe, an air screw in said frame arranged immediately below the base of said pipe, and means for rotating said screw.

7. A tank-charging appliance comprising a frame, means for removably supporting said frame in the charging opening of the tank, an air screw rotatably mounted on said frame, and operating means carried by said frame for operating said air screw.

8. A tank-charging appliance comprising a frame, means for supporting said frame in the charging opening of the tank, air current developing means carried by said frame, and operating means mounted on said frame for operating said air current developing means.

In testimony whereof, I have signed my name to this specification, this 31st day of October, 1927.

CARL HUNTEMÜLLER.
